UNITED STATES PATENT OFFICE

114,098

DESIGN FOR A PIANO CASE

Thomas J. Dentz, New York, N. Y., assignor to Janssen Piano Co., Inc., Brooklyn, N. Y., a corporation of New York

Application January 7, 1938, Serial No. 74,139

Term of patent 3½ years

To all whom it may concern:

Be it known that I, Thomas J. Dentz, a citizen of the United States, residing at the Borough of Manhattan, in the city of New York and State of New York, have invented a new, original, and ornamental Design for a Piano Case, of which the following is a specification, reference being had to the accompanying drawing, forming part thereof.

Figure 1 is a perspective view of a piano case
showing my new design.

Figure 2 is another perspective view of a piano
case showing my new design and taken from a different position.

Figure 3 is an end view of the same case.

What I claim is:

The ornamental design for a piano case, as shown.

THOMAS J. DENTZ.
